US00D788329S

(12) **United States Design Patent** (10) **Patent No.:** **US D788,329 S**
Bizzarri et al. (45) **Date of Patent:** **** May 30, 2017**

(54) **POST COVER**(71) Applicant: **CPG International LLC**, Scranton, PA (US)(72) Inventors: **Paul M. Bizzarri**, Mason, OH (US); **Chip Herr**, Columbus, OH (US); **John M. Previte**, Dublin, OH (US); **Kevin T. Burt**, Columbus, OH (US); **William G. Taylor**, Columbus, OH (US); **Matthew T. Fenneman**, Gahanna, OH (US); **Jeffrey R. Burr**, Loveland, OH (US); **Timothy C. Rothwell**, Dublin, OH (US)(73) Assignee: **CPG International LLC**, Scranton, PA (US)(**) Term: **15 Years**(21) Appl. No.: **29/532,103**(22) Filed: **Jul. 1, 2015****Related U.S. Application Data**

(63) Continuation of application No. 13/461,496, filed on May 1, 2012, which is a continuation of application No. 12/831,064, filed on Jul. 6, 2010, now Pat. No. 8,167,275, which is a continuation of application No. 11/292,269, filed on Nov. 30, 2005, now abandoned.

(51) **LOC (10) Cl.** ..... **25-01**(52) **U.S. Cl.**USPC ..... **D25/133**(58) **Field of Classification Search**USPC D25/126-135; 256/1, 59, 22, 65.4, 69
